UNITED STATES PATENT OFFICE.

WIRT STANLEY QUIGLEY, OF PHILADELPHIA, PENNSYLVANIA, ASSIGNOR
TO KITSON HYDRO-CARBON HEATING & INCANDESCENT LIGHTING COM-
PANY, OF SAME PLACE..

OXYGEN CUT-OFF FOR HYDROCARBON-VAPOR LAMPS.

SPECIFICATION forming part of Letters Patent No. 668,455, dated February 19, 1901.

Application filed August 10, 1900. Serial No. 26,519. (No model.)

To all whom it may concern:

Be it known that I, WIRT STANLEY QUIGLEY, a citizen of the United States, residing at Philadelphia, in the county of Philadelphia and State of Pennsylvania, have invented certain new and useful Improvements in Oxygen Cut-Offs for Hydrocarbon-Vapor Lamps; and I do hereby declare that the following is a full, clear, and exact description of the invention, such as will enable others skilled in the art to which it appertains to make and use the same.

The invention provides certain improvements in and connected with hydrocarbon-lamps.

15 The primary object of the invention is to provide a means to prevent "flaming" of the oil, which often accumulates in the globe and naturally is readily ignited by the mantles and is a common source of annoyance.

20 Broadly considered, it consists in means for cutting off the oxygen to cause the extinguishing of the flames.

25 The nature, characteristic features, and scope of my invention will be more fully understood from the following description, taken in connection with the accompanying drawings, forming part hereof, and in which—

30 Figure 1 is a sectional elevation of a hydrocarbon-lamp, showing one means of carrying my invention into practice, the same consisting of a pivotal lever having forked arms carrying movable ferrules, the latter constituting a duplex closure. Fig. 2 is an elevation showing the ferrules in their closed position.

35 Fig. 3 is an elevation of a chimney, partly broken away to disclose another means, same consisting of hinged leaves operated by a rack and pinion; and Fig. 4 is a detail showing a top plan view of the hinged leaves illustrated in Fig. 3.

40 Referring to Figs. 1 and 2, A designates a hydrocarbon-lamp of the Kitson system, having chimney a, provided at its top with the gauze opening b and at its bottom with the apertured portion c, constituting the oxygen-supply, as usual. The chimney a has its lateral walls penetrated by pins d, which afford pivotal bearings for the forked arms e of a lever f. Each of said forked arms is provided

50 with the obliquely-arranged links g h, to either side of their axes, and said links serve to sustain the ferrule members i j, constituting the respective closures for the oxygen-inlet openings. The ferrules are slidably mounted upon the chimney and are of sufficient length to close the respective inlet-openings. The lever f may be provided with a chain k, and it will be apparent that when said lever is pulled down from its normal position, Fig. 1, to the position shown in Fig. 2 60 the ferrules i j will be retracted and will operate to respectively close the gauze top a and perforated bottom c.

65 In Fig. 3 I have shown a varied form of cut-off for closing the gauze top only. The same comprises two semicircular leaves i' j', which are properly mounted upon the pin l, so as to be capable of an upward swinging movement. The cut-off is shown in its closed position and as resting upon an annular ring or ledge m, 70 provided for the purpose. The means for operating this type of damper or cut-off is shown as preferably consisting of a slotted rack-bar n, having a vertical movement upon the guide-pins o, mounted in the side of the 75 chimney. The rack-bar is provided at its top with two diverging arms p p', which bear, respectively, against the leaves i' j'. A pinion q is suitably mounted in the chimney in 80 position to engage the rack-surface and is operated by an arm r, as in Fig. 3, in the present instance through the medium of chains s, two of which will be provided, one to raise and the other to lower the rack-bar.

85 As the cut-off need be in operation but a moment or so in order to extinguish the flames, sufficient oxygen will be present to feed the burners, and they will burn fairly well until the cut-off is opened, when they will resume their usual luminancy. The cut-off extinguishes only the flames from the burning oil in the bottom of the lamp and not the light of the lamp. This may be accounted for by the fact that sufficient oxygen is present in the combustible mixture supplied to the incandescents to keep them glowing, while during the period the cut-off is in action no oxygen can reach the burning oil,

which consequently must become extinguished.

It will be obvious to those skilled in the art to which my invention appertains that modifications may be made in detail without departing from the spirit thereof. Hence I do not limit myself to the precise construction and arrangement of parts hereinabove set forth, and illustrated in the accompanying drawings; but,

Having thus described the nature and objects of my invention, what I claim as new, and desire to secure by Letters Patent, is—

1. In a hydrocarbon-vapor lamp, the combination of a chimney having lateral air-passages, a device for closing said passages, and

an actuator for the device, movable in respect to the same, substantially as described.

2. In a hydrocarbon-vapor lamp, the combination of a chimney having lateral air-passages, ferrules slidably mounted upon the chimney and adapted for closing said passages, and mechanism, substantially as described, for operating said ferrules to, respectively, open or close the said passages, as and for the purpose set forth.

In testimony whereof I have hereunto signed my name.

WIRT STANLEY QUIGLEY.

In presence of—

ROBT. S. MONKHOUSE,
BENJAMIN J. COOKE.
